UNITED STATES PATENT OFFICE.

KONRAD KISSE, OF BERLIN, GERMANY.

REINFORCED-CONCRETE MAST.

Application filed July 8, 1922. Serial No. 573,537.

To all whom it may concern:

Be it known that I, KONRAD KISSE, a citizen of Germany, residing at Berlin, Germany, have invented certain new and useful Improvements in Reinforced-Concrete Masts, of which the following is a specification.

This invention has reference to reinforced concrete poles and it is intended to generally improve and facilitate the construction of poles of this kind, and to devise means for increasing the strength and the resistance thereof. As a substitute for the usual wooden or iron poles with their many inconveniences and disadvantages tubular reinforced concrete poles have been known for some time which have usually been made by centrifuging. These reinforced concrete poles, however, present great inconveniences, particularly in view of the high costs of erection and great weight involving considerable expense for transformation and mounting. Reinforced concrete poles of star-shaped section have also been suggested, but they present unfavorable structural conditions, inasmuch as they do not admit the insertion of suitable and sufficient reinforcements, so that a sufficient bending resistance is not obtainable, except by employing unduly large masses of material.

These inconveniences are overcome in accordance with my invention by providing the poles with a particularly favorable cross sectional shape. My invention is particularly distinguished by the fact that each web of a pole of star-shaped section terminates in a beam of hammer-like cross section in which the iron bars or rods provided for reinforcing purposes in the longitudinal direction can be spaced apart in a most favorable manner, while at the same time the concrete is closely encircled with iron in accordance with Considér's method, so as to produce inflexible beams at the ends of the webs and to obtain the maximum efficiency with the least expenditure of material.

My invention is shown by way of example upon the accompanying drawing in several forms of embodiment.

Figure 1 is a cross sectional view of the upper part of a pole.

Figure 2 is another cross sectional view of a lower portion of the pole.

Figure 3 is another cross section comprising a particularly advantageous form of reinforcement.

Figures 4 and 5 are details of the reinforcing means shown in Figure 3.

Figure 6 is a cross sectional view of another modification of reinforcement of the pole.

Figures 7 and 8 are details of the reinforcement shown in Figure 6.

As shown in Figures 1 and 2, the radial webs 2 are provided at their outer ends with beams 1 of hammer-like cross section by which great tensile strength is obtained. In consequence thereof, such radial webs may be comparatively thin-walled. As appears from Figure 2, all parts of its cross section are enlarged in downward direction. The hammer-shaped beams 1 of the pole are connected at certain intervals by transverse ribs 3 or the like which assist in preventing lateral bending.

Longitudinal reinforcing bars 4 are arranged in the hammer-shaped beams 1 and in the centre of the pole a longitudinally extending rod 5 is mounted which may be replaced by a tube, in case that it is desired to pass conduits, conductors or the like through the pole. Reinforcing in transverse direction may be effected in the usual manner by means of struts or clips (not shown) which surround the longitudinal irons 4 in the hammer-shaped beams and the rod 5 in the middle of the post. It is, however, preferable, particularly in order to facilitate manufacture, to effect transverse reinforcement in a manner well known per se by means of spirally wound wires or iron rods.

For the purpose of fixing the spirally wound wires 8 iron loops 6 and 7 may be employed, the loops 6 being placed around the rods 4, while loops 7 are placed around the central rod 5, their hook-shaped ends engaging the wires 8 and retaining the same in position.

Instead of the rods and wire loops referred to, I can also employ, according to Figures 6-8, angle irons 9 the web portions of which are provided with indentations or hooked-shaped projections 11, the wires 8 being wound around the angle irons and secured in position in the hooks 11.

The relatively narrow spaces between the reinforcing members interfere, of course, with the introduction of the concrete. It is advisable, therefore, to employ thin liquid concrete in making these poles and to make provision for securing a uniform and thorough distribution of the concrete

throughout the mast. This may for instance be effected by striking the mould from without with suitable hammers operated by compressed air or by mechanical means, while filling the mould with concrete. By this operation the concrete is not only forced into all the parts of the mould, but also all iron parts are completely surrounded with concrete, while the formation of air bubbles is avoided, inasmuch as such bubbles are detached from the iron by the hammer blows and are caused to rise to the surface. I also prefer subjecting those parts of the reinforcing rods or bars which project from the concrete to vibration by striking them with the hammer, thereby submitting all iron parts to violent vibration which causes the air bubbles still adhering thereto to become detached.

20 Other means of connecting the several parts and of securing their uniform arrangement may be employed in connection with my invention, and various modifications and changes may be made to particularly adapt 25 the invention to varying conditions of application.

I claim:—

1. Reenforced concrete pole comprising three concrete beams of substantially triangular cross section disposed about a common centre with one side of each pole averted from said centre, concrete webs of smaller cross-sectional area extending from said beams inwards and meeting in said centre, a longitudinal reenforcing member in said centre and a plurality of longitudinal reenforcing members in each beam.

2. Reenforced concrete pole comprising three concrete beams of substantially triangular cross section disposed about a common centre with one side of each pole averted from said centre, concrete webs of smaller cross sectional area extending from said beam inwards and meeting in said centre, a longitudinal reenforcing member in said centre and a longitudinal reenforcing member in each corner of each beam.

3. Reenforced concrete pole comprising three concrete beams of substantially triangular cross section disposed about a common centre with one side of each pole averted from said centre, concrete webs of smaller cross sectional area extending from said

beams inwards and meeting in said centre, a longitudinal reenforcing member in said centre, a plurality of longitudinal reenforcing members in each beam and transverse reenforcing members extending from said beams across said webs to said centre.

4. Reenforced concrete pole comprising 60 three concrete beams of substantially triangular cross section disposed about a common centre with one side of each pole averted from said centre, concrete webs of smaller cross sectional area extending from said beams inwards and meeting in said centre, a longitudinal reenforcing member in said centre, a longitudinal reenforcing member in each corner of each beam and transverse reenforcing members extending from said 70 central reenforcing member across said webs to and around the reenforcing members in said beams.

5. Reenforced concrete pole comprising 75 longitudinally and radially extending concrete webs forming the central body, longitudinally extending concrete beams of hammer-like cross section at the outer ends of said webs, a central longitudinal reenforcing member extending in the meeting 80 point of said radial webs, a plurality of lateral longitudinal reenforcing members in each of said beams, transverse reenforcing means extending from said lateral members across said webs to said central member and hooks formed on said lateral members for fixing said transverse reenforcing means in position on said members.

6. Reenforced concrete pole comprising 90 longitudinally and radially extending concrete webs forming the central body, longitudinally extending concrete beams of hammer-like cross-section at the outer ends of said webs, a central longitudinal reenforcing member extending in the meeting point 95 of said radial webs, a plurality of lateral longitudinal reenforcing members of angular cross section in each of said beams, transverse reenforcing means extending from said lateral members across said webs to said 100 central member and hooks formed on said lateral members for fixing said transverse reenforcing means in position on said members.

In testimony whereof I affix my signature.
KONRAD KISSE.
